(57) **CLAIM**

We claim the ornamental design for a control panel for hand-held device, as shown and described.

DESCRIPTION

FIG. 1 is a front elevation view of the control panel for hand held device showing my new design, the broken line showing of the environment is for illustrative purposes only and forms no part of the claimed design.

FIG. 2 is a side elevation view of the control panel;

FIG. 3 is a front elevation view thereof;

FIG. 4 is a top plan view thereof; and,

FIG. 5 is a bottom plan view thereof.
